[57] **CLAIM**

The ornamental design for a protective hail cover for vehicles, as shown and described.

DESCRIPTION

FIG. 1 is a front elevational view of the protective hail cover for vehicles showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

FIG. 7 is a sectional side view taken vertically through the mid-plane of the cover at line 7—7 of FIG. 5.

The automobile shown in broken lines in FIG. 3 is for illustrative purposes only and form no part of the claimed design.
